CLAIM

The ornamental design for a single-direction diverting pusher element for a sorting conveyor, as shown and described.

DESCRIPTION

FIG. 1 is a top, front and right side perspective view of the right hand single-direction diverting pusher element for a sorting conveyor of the present invention showing our new design

FIG. 2 is a left side elevational view of the pusher element of FIG. 1.

FIG. 3 is a top plan view of the pusher element of FIG. 1. FIG. 4 is a right side elevational view of the pusher element of FIG. 1.

FIG. 5 is a front elevational view of the pusher element of FIG. 1.

FIG. 6 is a rear elevational view of the pusher element of FIG. 1.

FIG. 7 is a top, front and left side perspective view of a second embodiment of the present invention showing our new design.

FIG. 8 is a right side elevational view of the pusher element of FIG. 7.

FIG. 9 is a top plan view of the pusher element of FIG. 7. FIG. 10 is a left side elevational view of the pusher element of FIG. 7.

FIG. 11 is a front elevational view of the pusher element of FIG. 7; and,

FIG. 12 is a rear view of the pusher element of FIG. 7. The pusher element of FIGS. 7 through 12 is an identical mirror image of the pusher element of FIGS. 1 through 6. The bottom of the pusher element varies with the type of pusher element mount used and does not constitute a part of the invention.
